UNITED STATES PATENT OFFICE.

EDWARD J. RUSSELL, OF COATESVILLE, PENNSYLVANIA.

COOLING SYSTEM FOR OPEN FURNACE FRONTS.

1,411,186.

Specification of Letters Patent. Patented Mar. 28, 1922.

Application filed November 13, 1920. Serial No. 423,932.

To all whom it may concern:

Be it known that I, EDWARD J. RUSSELL, a citizen of the United States, residing at Coatesville, in the county of Chester and State of Pennsylvania, have invented new and useful Improvements in Cooling Systems for Open Furnace Fronts, of which the following is a specification.

This invention relates to cooling systems for furnaces and is especially adapted for application upon open hearth furnaces for the purpose of protecting the skewback and to provide cooling means whereby underpinning or other hot repair work may be rendered more comfortable for the workman.

Another object is the provision of a cooling system which may be readily installed in an open hearth furnace of the usual type, without altering the construction of the furnace.

A further object is the provision of a cooling system which is simple of construction and effective in operation, which may be installed at a nominal cost.

With the above and other objects in view, the invention further includes the following novel features and details of construction, to be hereinafter more fully described, illustrated in the accompanying drawings and pointed out in the appended claims.

In the drawings:

Figure 1 is a rear elevation of an open hearth furnace on the line 1—1 of Figure 2 with portions of the brick work broken away to show the invention applied thereto.

Figure 2 is a vertical section of the same taken at right angles to Figure 1 on the line 2—2.

Figure 3 is a similar view on the line 3—3 of Figure 1.

Figure 4 is a detail perspective view of the tank and its hangers removed from the furnace.

Figure 5 is a longitudinal horizontal sectional view of the tank.

Referring to the drawings in detail, wherein like characters of reference denote corresponding parts, the reference character 10 indicates the door of an open hearth furnace, above which is arranged the usual skewback 11 which is supported in the ordinary manner by channel bars 12 and 12', the furnace arch being shown at 13.

The invention includes a tank 14 which is primarily supported in position by hangers 15 and 16, the said hangers having one end connected to the tank and their opposite ends formed into hooks 17 which engage over the channel bar 12. If desired, additional supports may be provided in the form of brackets 18 having one arm secured to the furnace and the other arm disposed beneath the tank 14.

This tank which is preferably of cellular construction is adapted to receive a supply of water through a feed pipe 19, one end of which communicates with the interior of the tank, while its opposite end may communicate with a suitable source of water supply, such as the usual service pipe, or by gravity and the usual water tank be installed over the furnace.

The hanger 16 is of hollow construction and has one end in communication with the interior of the tank 14, while its opposite end may be connected to a discharge pipe 20 which serves as a disposal for the waste water.

From the foregoing description and the accompanying drawings it will be apparent that the invention provides a water cooling system which is built in with the arched brick work and prevents the superposed brick work from burning and crumbling away. It will protect the skewback and leave a smooth surface against the cooler, so that underpinning or other hot repair work will be rendered less disagreeable to the workman. All hot repair work may be made from the outside of the furnace, thus the time required for repairs will be materially reduced and a saving of labor and material effected.

The invention is susceptible of various changes in its form, proportions and minor details of construction and the right is herein reserved to make such changes as properly fall within the scope of the appended claims.

Having described the invention what is claimed is:

1. The combination with a furnace, of a tank disposed above the door thereof, hangers having one end secured to the tank and their opposite ends hooked from the skewback support for primarily supporting the tank in position, one of said hangers being hollow to define and outlet conduit

and means whereby water may be supplied to the tanks.

2. In combination with a furnace and support therefor, of an elongated cellular tank,
5 a solid hanger extending from one end of said tank and engaging said support, a hollow hanger extending from the opposite end

of said tank and engaging said support, means for supplying water to said tank and a vertical discharge pipe connected to said ¹⁰ hollow hanger.

In testimony whereof I affix my signature.

EDWARD J. RUSSELL.
